UNITED STATES PATENT OFFICE.

DONALD J. JOHNSON, OF MOZART, SASKATCHEWAN, CANADA.

GRAIN-BINDING MACHINE.

Application filed January 26, 1921. Serial No. 439,962.

To all whom it may concern:

Be it known that I, DONALD J. JOHNSON, a subject of the King of England, and a resident of the city of Mozart, Province of 5 Saskatchewan, Dominion of Canada, have invented certain new and useful Improvements in Grain-Binding Machines, of which the following is a specification.

This invention relates to improvements in 10 grain binding machines, more particularly it relates to the construction and application of automatically operating, bundle carrier dumping mechanism for use on all grain binders of the usual well-known types.

15 The principal object of the invention resides in the construction of mechanism that may be readily applied to the already existing parts of these machines without change or alteration of the latter, and which will 20 operate in such manner that, after a predetermined number of bundles have been formed and delivered onto the bundle carrier, the latter will be automatically dumped to discharge the bundles onto the ground 25 and will then be returned to initial position.

It is also an object of the invention to provide mechanism of the above character which can be made to idle if it is desired 30 that the carrier be operated by the usual foot lever mechanism, or if it is desired to carry over one or more bundles for re-adjusting the dumping points.

Further objects of the invention reside in the novel construction of the different parts 35 of the mechanism and in their combination with the operating parts of the machine, to produce an operative attachment.

In accomplishing these and other objects 40 of the invention, I have provided the improved details of construction, the preferred forms of which are illustrated in the accompanying drawings, wherein—

Figure 1 is a front elevation of a part 45 of a grain binding machine whereon the present mechanism is mounted, showing the main wheel whereby the machine parts are driven, the bundle carrier, and dumping mechanism whereby the carrier is controlled.

Figure 2 is a plan view of the operating 50 parts of the machine, as shown in Figure 1, illustrating the driving connections of the various parts of the present mechanism and parts of the machine.

Figure 3 is a perspective view of the already 55 provided foot dump mechanism, showing the attachment thereto of the

spring for returning the carrier to normal position for receiving bundles after a dumping operation.

Figure 4 is a perspective, front view of a 60 portion of the binding machine showing the dump crank, connected at one end with the foot lever rod and at its opposite end with the bundle carrier, also showing the bracket wherfrom the ratchet wheel of the present 65 mechanism is carried and the trip arms fixed to the dump crank.

Figure 5 is an enlarged, front view of parts of the dumping mechanism.

Figure 6 is a plan view of the parts shown 70 in Figure 5.

Figure 7 is an enlarged, sectional detail taken on the line 7—7, Figure 6, particularly illustrating the resetting mechanism for insuring the return of the bundle carrier 75 to normal position after being dumped.

Figure 8 is an under side, plan view of the resetting arm.

Figure 9 is a detail view showing the manner of mounting and the character of 80 the crank shaft interposed between the bundle forming mechanism and the ratchet wheel.

Referring more in detail to the several views of the drawings, wherein like reference numerals designate the same or like parts—

1 designates the main, or driving wheel, of a binder whereto the present mechanism is attached, and 2 and 3 respectively designate front and rearward, longitudinal frame beams between which the wheel 1 operates and which are connected at opposite sides of the wheel by cross bars 4, as shown in Figure 2; the wheel being mounted to support the frame and to drive the cutting and binding mechanism. Supported at one side of the wheel by means of uprights 5 and 6, Figure 1, is an elevator, designated at 7, whereby the grain which falls, after being cut, onto the platform, not shown, is delivered over the wheel and into a receiver 8 which extends downwardly at the opposite side of the wheel and wherein the grain is bound in bundles before being delivered 105 onto the carrier arms 9.

A shaft 10 is mounted transversely of the frame, beneath the binding mechanism, which is equipped at its forward end with a fly wheel 11 whereto one end of a pitman 12, which operates the grain cutting sickle 13, Figure 2, is attached. Near its rear-

ward end the shaft 10 has a gear wheel 14 keyed thereon, Figure 2, driven by a larger gear 15 meshing therewith which is fixed on one end of a shaft 16 mounted at the rear of the wheel 1 between the cross bars 4 and driven by a chain 17 operating over sprocket wheels 18 and 19 respectively on the shaft and wheel 1.

Supported in frame members, at a point 10 somewhat above the shaft 10, and parallel thereto, is what is known as the packer shaft 20, which operates mechanism which forms the bundles of grain. This is driven from the shaft 10 by a chain belt 21 operating over sprocket wheels 22 and 23 at the rearward ends of these shafts. At its forward end, the shaft 20 has a driving connection with the shaft 25 of bundle discharge mechanism; the shaft being mounted upon 15 the receiver 8, Figure 1; and the driving connection comprises a shaft 26 equipped at one end with a gear wheel 27 which meshes with a similar gear 28 on the shaft 20, and at its opposite end has a gear 29 which drives a relatively large gear wheel 30 on the shaft 25.

Beneath the receiver is mounted the needle actuating shaft 31, equipped at one end with a crank arm 32 which is actuated by means 30 of a rod 33 connected with the periphery of wheel 30.

Briefly stated, the operation of the binding mechanism is as follows: As the binder is moved forwardly, the main wheel rotates 35 and by means of the chain belt 17, rotates the shaft 16 to drive, through the connections disclosed, the shafts 10, 20 and 25. The needle actuating shaft 31 operates in synchronism with mechanism not shown and 40 with the shaft 25 to project the needle designated at 34 to carry the binding twine about the bundles formed in the receiver, and the discharge arms 35, fixed on the shaft 25, engage the formed bundles to deliver them 45 onto the bundle carrier arms 9.

The arms 9 of the bundle carrier are fixed in a horizontally mounted shaft 40 supported from the frame at a point below the discharge end of the receiver 8 so as to normally extend horizontally as shown in Figure 1. This shaft 40 is adapted, however, to be partially rotated to tilt the arms downwardly to discharge the bundles onto the ground. The usual manually controlled 50 mechanism for actuating the carrier comprises a dump crank 41 (see Figs. 1 and 4) which is supported in an inclined manner along the front of the machine within bearings 42 and 43 adjacent its ends. At its 55 lower end it has a downwardly turned crank arm 44 to which is pivotally fixed the lower end of a link 45 which latter at its upper end, is connected with a rocker arm 46 for rotating the tube 40, the connection being 60 such that rotation of the dump crank which

will swing the arm 44 upwardly, will permit the tube 40 to rotate to move the arms 9 downward to dump the bundles therefrom.

At its upper end the dump crank has a forwardly turned arm 47 to which is fixed the forward end of a foot rod 48 that extends toward the rear of the machine to adjacent a driver's seat, as shown in Figure. 3, and at that end is supported by a crank arm 49, and is equipped with a foot rest 50 70 against which pressure may be applied to return the carrier after it has been dumped.

I make no claim to the above mechanism since it is the same as that now in general use, but have described it in a general way 80 in order that a clearer understanding may be had of the operation of parts which I have applied thereto and which embody the present invention.

Fixed to the frame upright 5 in such manner as to extend forwardly therefrom at a point just above the dump crank 41, as shown in Figures 1, 2 and 4, is a bracket 51 having a trunnion 51' at its outer end whereon a ratchet disk 52 is rotatably mounted. 90 This disk has an arm 53 fixed on its outer face and extended in a radial direction beyond its edge, and which is adapted, as the disk is rotatably advanced, to engage a trip arm 54 that is fixed to the dump crank 41 to 95 move the said arm upwardly and thereby rotate the trip crank to actuate the bundle carrier arms to unloading position.

The means whereby the disk 52 is rotatably advanced comprises mechanism including a shaft 55, that is rotatably supported adjacent the outer side of the wheel 1 and parallel with the shafts 10 and 20. At its forward end the shaft is provided with a crank arm 56 which is connected by means of a link 57 with the pitman 33 so that, as the latter is reciprocated by rotation of the wheel 30, the shaft 55 will be partially rotated back and forth accordingly as the pitman operates.

Near the forward end of the shaft 55 and in alignment with the disk 52, is a crank arm 60, and fixed to the outer end thereof is a link 61 which has a folded end portion 62 at the free end overlying the upper edge of the ratchet disk 52 and which has a transverse pin 63 through this end, (see Fig. 5) adapted to engage within the notches of the disk so that, with each reciprocation, it rotatably advances the disk the distance of 115 the spacing of the notches, which in the present device is ninety degrees, requiring four reciprocations for each revolution of the disk.

Since, in machines of this character, the 125 shafts 20 and 31 are carried by frame parts that are shiftable forwardly or rearwardly with respect to the frame, for the accommodation or proper bundling of grains of different height, it is necessary that there be a 130

sliding connection between the shaft 55 and the crank arm 60 which is connected with parts that have no adjustment forwardly or rearwardly. The character of the shaft, 5 and the manner in which it is shifted is illustrated best in Figure 9, wherein 70 and 71 respectively designate upwardly sloping beams which are a permanent part of the frame of the machine. Fixed to the beam 10 70 is a bearing 72 through which the rearward end of the shaft is slidably mounted, and fixed to the beam 71 is an arm 73 which extends forwardly and has spaced apart bearing yokes 74 and 74' thereon containing 15 rotatable sleeves 75 and 75' through which a squared portion 55' of the shaft is slidably extended. The crank arm 60 is mounted on this squared portion between the yoke arms, so that it is retained functionally connected 20 and in position regardless of shifting of the shaft 55. In this figure 9, 80 designates a part of the packer frame which is shiftable forwardly and rearwardly as before mentioned, and secured thereto is an arm 81 which has an end yoke 82 extended between 25 collars 83 and 83' secured to the shaft 55, so that shifting of the packer frame will shift the shaft 55 accordingly.

When the bundle carrier is in receiving or 30 carrying position, as shown in Figure 1, the crank arm 44 at the lower end of the dump crank 41 extends downwardly so that its outer end is slightly beyond the dead center line, with respect to the connecting link 45 35 which operates the carrier, and the carrier load tends, not to cause dumping, but to resist dumping. After the arm 54 on the dump crank has been engaged by the arm 53 extending from the disk 52, to actuate the 40 dump crank to dump the carrier, this crank arm 44 extends substantially in a horizontal position, and the arm 47 at its opposite end, as illustrated in dotted lines in Figure 3, stands substantially vertical.

45 As soon as a load has been discharged from the carrier, it is free to be returned to initial position for receiving following bundles of grain, and, to provide for automatically returning the carrier, I have attached 50 a spring 85, as best shown in Figure 3, at one end to the rod 48 adjacent the foot rest 50 and at its opposite end to the frame upright 6. This spring under normal conditions will by itself return the carrier, but in 55 order that the latter will be returned under all conditions, I provide the rod 41 with a return arm 88 which is fixed thereto to extend along the edge of the disk 52 at the side opposite the arm 54 and which is actuated 60 downwardly by the downward travel of the arm 53 fixed on the disk.

The arm 88, at its outer end, has a star shaped wheel 89 rotatably mounted therein, as shown in Figure 8, with the points 89' of 65 the wheel extended in such position as to be

engaged by the arm 53 on its downward movement. Normally the wheel is prevented from rotating so that, through it, the arm 88 will be moved downwardly until the carrier is reset and the lever arm 44 on the dump crank 41 carried below its dead center position before mentioned, when, at this time, the star wheel is permitted to rotate so that the arm 53 may pass.

The means provided for retaining the star 75 wheel from rotating so that when it is engaged by the downward movement of the arm 53, it will act to move the arm 88 downwardly, comprises a locking bar 90, (see Figs. 6, 7 and 8) which is centrally pivoted 80 on the under side of the arm 88 with one end adapted to extend between the points of the wheel to prevent the latter from rotating, and which has its opposite end turned laterally to one side of the arm. The star wheel 85 is thereby locked against rotation while the arm is being moved downwardly to return the bundle carrier to receiving position. As soon as the carrier is returned, the star wheel is released so that it may rotate and 90 permit the arm 53 to pass. The means for releasing comprises an arm 94 which is fixed to the upright 5 and extends downwardly adjacent the arm 88 in such position as to be engaged by the outturned end of the bar 90 95 to press the latter inwardly as the arm 88 swings downwardly, and to finally cause it to release the star wheel. When the arm 88 is again raised, the bar 90 is urged again 100 into locking relation with the wheel by means of a spring 91 which is fixed to the arm and bears against the bar.

To prevent possible backward movement of the disk 52, I have fixed a spring arm 96 to the beam 5 below the disk, with one end 105 yieldingingly engaging the edge of the disk, as shown in Figure 5, and adapted to seat in the notches therein.

Should it be desired that the automatic tripping mechanism be temporarily disconnected 110 for any reason, I have provided a cable 98 which is fixed to the arm 61 and extends to adjacent the driver's seat, and which can be drawn in to cause the arm to be raised from the disk 52. If the binder was 115 being drawn by a tractor, this cable could be extended to the tractor and operated from that position.

Assuming that the different parts of the 120 mechanism are so constructed and are assembled with the operating parts of a binder as described, in operation, the binder is drawn forward through the field of grain, which is cut by the sickle 13, and delivered by the elevator 7 to the bundle forming 125 mechanism which operates to bind and deliver the grain in bundles onto the carrier arms 9. With the discharge of each bundle onto the carrier, the wheel 30 makes one revolution, and this, by means of the mecha- 130

nism previously described, causes the disk 52 to be advanced one-fourth of a revolution. With the discharge of the fourth bundle, the arm 53 on the disk 52, engages the trip arm 54 to rotate the shaft 41 to cause the carrier to be dumped, and as soon as the load is delivered onto the ground the spring 85 under normal conditions causes the carrier to be returned. Should the carrier fail to completely return, the arm 53 will, with the delivery of the next bundle, be brought into engagement with the arm 88 to positively reset the carrier.

It is apparent that disks 52, equipped with various numbers of notches could be used if it was desired to carry fewer or more bundles.

It is also apparent that various changes in the manner of attaching the different parts could be made without departing from the spirit of the invention, and I do not wish to limit my claims only to the construction shown.

Having thus described my invention, what I claim as new therein and desire to secure by Letters Patent is:

1. In a machine of the class described, the combination with a bundle carrier, a bundle forming mechanism, mechanism operating intermittently to discharge formed bundles singly onto the carrier, and a dumping crank operatively connected with said carrier and operable to move the same between carrying and dumping positions, of a ratchet disk rotatably mounted adjacent said dump crank, a trip arm extending radially from said disk, arms fixed to said dump crank to extend adjacent opposite sides of said disk in such position as to be actuated by said trip arm, and means operatively connected with said bundle delivery mechanism for rotatably advancing the disk through a certain interval with the delivery of each bundle onto the carrier to cause said trip arm, after the delivery of a certain predetermined number of bundles to actuate one of said dump crank arms to rotate said crank to dump said carrier and after a continued advance to actuate the opposite arm to return the carrier to initial position.

2. In a machine of the class described the combination with a bundle carrier, a bundle forming mechanism, mechanism operating intermittently to deliver formed bundles singly onto said carrier, and a dumping crank operatively connected at one end with said carrier to move the latter between dumping and carrying positions, and at its opposite end with foot actuated return mechanism, of a ratchet disk rotatably mounted adjacent said dump crank, an arm fixed to said dump crank and extending adjacent said disk, a trip arm fixed to said disk and extending radially in position to engage said crank arm, a disk advancing

link mounted to be reciprocated by action of said bundle discharge mechanism and engaging said disk to rotatably advance the same to cause said trip arm to actuate said crank arm to dump said carrier, and a spring fixed to said foot return mechanism whereby, after being dumped, the carrier is automatically returned to initial position.

3. In a machine of the class described, the combination with a bundle carrier, means for forming grain into bundles, an intermittently rotating shaft operable to deliver formed bundles onto said carrier, a reciprocating link for actuating a needle operating shaft, and a rotatable dump crank shaft for actuating said carrier between carrying and dumping positions, of a ratchet disk mounted rotatably adjacent said dump crank shaft, a trip arm fixed to extend radially from the disk, dumping and returning arms fixed to said dump crank shaft to extend at opposite sides of the disk to be respectively actuated by said trip arm on rotation of the disk to rotatably move said dump crank to dump the carrier and then to return it to the initial position, a shaft mounted slidably and rotatably in the machine between the bundle forming mechanism and disk, and having a pair of crank arms thereon, a link connected with one of said crank arms and with said reciprocating needle actuating link, and an advancing link fixed at one end to the other of said crank arms and at its opposite end adapted to engage said ratchet disk to rotatably advance the latter a definite interval with each reciprocation of the needle actuating link for the purpose set forth.

4. In a machine of the class described, the combination with a bundle carrier, means for forming grain into bundles and for delivering bundles singly onto the carrier, of a rotatable dumping crank shaft operable to actuate said carrier between carrying and dumping position, of a ratchet disk rotatably mounted adjacent said dump crank, a trip arm fixed to extend radially from said disk, dumping and returning arms fixed to said dump crank to extend adjacent opposite edges of said disk to be actuated by said trip arm, an advancing link operatively connected at one end to be moved reciprocally by the bundle delivery mechanism and at its opposite end to engage said disk to rotatably advance the latter through a definite interval with the delivery of each bundle, and means for temporarily disengaging said advancing link from the disk for the purpose set forth.

5. In a machine of the class described, the combination with a bundle carrier, means for forming grain into bundles and for delivering bundles singly onto the carrier, of a rotatable dumping crank shaft operable to actuate said carrier between carrying and

dumping position, of a ratchet disk rotatably mounted adjacent said dump crank, a trip arm fixed to extend radially from said disk, a dump arm fixed to said dump crank 5 to extend adjacent one side of said disk to be engaged by upward travel of said trip arm to cause said crank to dump the carrier, a returning arm fixed to the dump crank shaft to extend along the opposite 10 side of the disk, having a wheel rotatably fixed in the end thereof having radially extending points to be engaged by said trip arm on its downward travel, a locking device on the arm for normally engaging said 15 wheel to prevent rotation thereof and an arm fixed to the machine adapted to engage said locking device to cause it to release the said wheel when said arm has been moved to its limit of travel for resetting the bundle carrier, an advancing link operatively connected at one end to be moved reciprocally by the bundle delivery mechanism and at its opposite end to engage said disk to rotatably advance the latter through a definite interval with the delivery of each 20 bundle, and means for temporarily disengaging said advancing link from the disk for the purpose set forth.

Signed at Seattle, Washington, this 21st day of January, 1921.

DONALD J. JOHNSON.
